Mellen Ballte April 4, 1810
Letters Patent (Published April 4, 1810)

The schedule referred to in these Letters patent and making part of the same, containing a description in the words of the said Mellen Ballte himself of his American wheelwright Labor saving Machine.

The frame of the Machine should be fourteen feet six inches long, eleven feet sixteen square feet high, the frame will consist of four corner posts,.... seven inches square, four girts seven inches square, to lie horizontally in the frame, two feet six inches from the floor, the cross girt seven by six inches square, to lie lengthwise in the frame, two feet from one side, and two feet six inches from the floor, two girts seven by six inches square to lie four feet six inches apart, and four feet six inches from one end, two feet six inches from the floor. Four plates five by three inches square framed into the head of the four corner posts seven feet from the floor, one girt five by three inches square, lying lengthwise in the frame seven feet from the floor, three feet six inches from one side, one counter-girt seven feet long lying three inches square, and four feet from one end into which a girt is framed five by three inches square and two feet long lying lengthwise in the frame, on which hang two fender posts, six inches square which reach the floor; the Machinery will consist of one main upright wheel five feet in diameter four inches thick, in the rim of which will be placed three iron bars four inches from the circumference the said bars are to be placed in the same manner as they are in a common plowman's wheel hangs upon a shaft of iron one inch and a half square, three feet six inches long, near the middle connected with the wheel a cylinder of one foot nine inches long and threaded in diameter, likewise on said shaft connected with said cylinder a double scroll to raise nine inches, one scroll plays upon iron pins through a wooden shaft nine by three inches square seven feet long; on the end of said shaft and two feet six inches from the iron pins, will be fixed an iron head in the form of a hammer in the face and under side of which, will be a socket to receive a double bar.

one inch wide and about thick, and on the side of said lower hand, will be a groove to receive the Butter that makes ride, said shaft will play up and down between the four supports, said lower hand will play by the side of an upright piece with a groove in the side to receive a spoke, in such a manner that the Butter in the lower hand will turn, said spoke there will be parallel with the shaft of the main cylinder a cylinder of wood through which passes an iron spindle in the end of which is a saw bit for the purpose of turning the other end of the spoke and Pointing the Hub, also a carriage to locate the Hub and spoke to the saw bit the said bit is turned by a strap passing over its cylinder as to the main cylinder, by the side of the face of the main wheel stands a brass carriage, with a groove suitable to receive a spoke, being in such manner that when the spoke is in the groove it will carry it to the face of the main wheel, in such a manner that the jointed iron in said wheel will draft it, likewise a socket in the end of the main shaft to receive an auger for boring the center of the Hub, also a carriage that will carry the hub to the auger, and from said carriage to the end of the main shaft will run an iron spindle for the purpose of turning the rim of a wheel, there will be and iron spindle parallel with the main shaft four feet six inches long one inch and half square, and on said spindle will be a wooden cylinder to receive a strap which leads to the main cylinder, likewise on said spindle will be two bevel wheels and one pinion, said wheels will stand with their bevels facing each other and at such distance as to receive between them two revolving bevel wheels, said wheels are to be a second iron, cut to the end of said spindle stands two collars, between which works a iron hand and one end of which is made fast the other end of said hand plays in a transverse grooving in the rim of a wooden wheel, said wooden wheel hangs upon a

spindle parallel with the aforesaid spindle, having one foot six inches long and one inch square, and on the end of said spindle hangs an iron wheel which is turned by a pinion upon the end of a spindle which passes through a large iron upright connecting wheel which is turned by a pinion upon the spindle containing the two level wheels, the motion of said wheels will be six turns to the regulating wheel once, said connecting wheel works into a pinion of six inches long and four inches diameter, through said spindle by another horizontal spindle, in the end of which is a bit, said pinion turns a pinion of four inches diameter and one inch thick, through which runs another horizontal spindle in the end of which is a bit, said spindle will lie in such a manner as to bore the bar's eye mortise in a nut, on each end of said spindle, there will be a collar of six inches long and said collars work upon four wooden blocks, on each end of said blocks are screws and nuts, and on the end of said spindles on the opposite end of the bit is a iron plate with each end for bit, through the center of the plate is a screw upon a spindle having through a bit wheel which turns a lower iron spindle with two level wheels one of which plugs in the reversing wheel, on horizontal face wheel four feet six inches in diameter, said wheel to be of wood or iron the top of said wheel to be two feet six inches from the floor; and the said wheel is turned by an upright wheel of iron, which hangs upon an iron spindle, and on the end of said spindle, hangs an iron level wheel which is turned by the reversing level wheel, said face wheel turns four iron upright wheels hung upon four iron spindles laying in such a manner, that with bits in the end of said spindles they will bore a hollow, in the opposite end of the spindles containing the four bits is a screw working in the collar, all the collars contain screws and nuts so that they are moveable, all of said spindles containing bits are driven to any given distance by means of the screws and collars on the end of the spindles and return by the reversing

and regulating wheel, also two Phenomenon blocks that hold the
wheel when its' loose, there is an shaft of seven feet hanging upon
the top of the frame over which are three cylinders, upon one Cyl-
inder is a strap leading to the Cylinder of the main wheel,
and from the other two Cylinders run two bands to two wheels,
said wheels being upon two iron spindles on the spindles is a
collar to project out half an inch; between the collars hangs two
bars always laying in such manner as to saw off both ends of a
tallow at any given length with their proper bevel. Said tallow
resists the saws by means of a block on which it is fastened
which moves by means of a lever, a strap from the main
Cylinder leading over another Cylinder over which is an iron
crank applied to which is a Pitman leading to the sawgate which
hangs upon the aforesaid guides Posts, in said gate hangs two
saws said saws contain teeth on both sides standing to-
wards the Guide Posts, on the side of the sawgate is a square
carriage which moves up the saws between the sawgate by
means of a screw to any assigned distance, and on said Car-
riage is a reversing carriage, which turns upon a centre
in the middle of the square carriage, the reversing carriage
is moved backwards and forwards by means of a hand
and cog and two fly wheels with teeth both ways, on the
shaft leading through the fly wheels is a pinion working
a rach on the reversing carriage.

Witnesses.
